DISPLAY DEVICE

Ira G. Haas, Far Rockaway, N. Y.

Application April 26, 1933. Serial No. 667,954

5 Claims. (Cl. 49—126)

This invention relates to display devices, such as that shown in my Patent No. 1,818,799, issued August 11, 1931, designed for use in window and counter displays for the purpose of pictorially representing articles of merchandise for the purpose and use thereof.

It is the general object and purpose of my present improvements to provide a foldable or collapsible display device embodying in a general way the principles of said patented device, and provided with simple and easily manipulable means for rigidly retaining the several co-operating parts thereof in their erect or set up positions.

More particularly, in one embodiment of my present invention, I provide a base structure consisting of upper and lower sections of heavy cardboard or other material, and means connecting said sections together along their corresponding longitudinal edges whereby said sections may be relatively moved to and from collapsed superimposed relation into spaced apart parallel relation, together with a display panel fixedly attached at one of its ends to one of said connecting means between the base sections, and members flexibly connected to the lower base section and movable through slots in the upper base section to erect positions upon movement of said panel to an upright position relative to the base.

It is a further general object of the invention to provide a display device as above characterized, the several parts of which are of very simple construction, as well as inexpensive to manufacture, and strong and durable.

With the above and other objects in view, the invention consists in the improved display device, and in the form, construction and relative arrangement of its several parts as will be hereinafter more fully described, illustrated in the accompanying drawing, and subsequently incorporated in the subjoined claims.

In the drawing wherein I have disclosed one simple and practical embodiment of the invention, and in which similar reference characters designate corresponding parts throughout the several views,—

Fig. 1 is a perspective view showing one practical embodiment of the invention;

Fig. 2 is a central transverse section;

Fig. 3 is a horizontal sectional view taken on the line 3—3 of Fig. 2; and

Fig. 4 is a sectional view similar to Fig. 2, showing the parts in folded or collapsed position.

Referring in detail to the drawing, the base of the display device includes upper and lower sections indicated at 5 and 6 respectively which may be produced from heavy cardboard or other suitable material. These base sections may be of any desired predetermined area, and along their corresponding front and rear longitudinal edges are hingedly connected with each other by the sections 7 which may likewise be of cardboard, and for convenience in manufacture, may be produced from integral portions of one or the other of the base sections 5 or 6.

To the rear section 7 of the base, a display panel 8 is suitably attached at its lower end for movement as a unit therewith.

The top section 6 of the base structure is provided with one or more slots 9 therein, and through these slots the display members 10 and 11 respectively are movably disposed, the said members being hingedly connected with the bottom section 5 of the base structure. As herein shown, the member 10 may be struck out from the material of said base section 5, while the other member 11 located adjacent one edge of said base section may constitute a part of the blank from which said section is cut.

An adjustable locking and supporting part generally indicated at 12 may also be die stamped or cut from the blank forming the base section 5 and remains hingedly connected therewith along the transverse fold line indicated at 13. The lower end of the panel 6 in line with the cut-out part of the base section 5, from which the adjustable support 12 is produced, is also provided with an opening as indicated at 14 so as to permit the upward swinging or hinging movement of the part 12 to an erect position. The free end of said part 12 is provided with a slot as indicated at 15 to receive the said panel 6.

The display member 10 is also provided at its lower end with a notch indicated at 16 to accommodate the part 12, said part which extends beneath the top section 6 of the base being provided with the slot 17 to receive the member 10, and thereby securely lock the same in erect position.

The top section 6 of the base at its rear edge also is cut away as at 18 to accommodate the upwardly extending portion of the part 12, said top section at one edge of said cut-out being provided with a tab or extension 19 to be received through the horizontal slot 20 in the part 12.

It will be apparent from the above description that when the device is arranged in its set-up position and the part 12 adjusted as shown in

Fig. 2 of the drawing, into locking engagement with the top section 6 of the base, the panel 8, and the member 10, the several parts will be rigidly sustained and held against accidental collapse, while the part 12 extending rearwardly of the panel 8 furnishes an easel or additional support tending to prevent accidental tipping over of the device from its proper position in the window or upon the counter.

10 When it is desired to collapse the device, it is only necessary to move the part 12 from its vertical position to a horizontal position in the plane of the base section 5. The panel 8 may then be moved forwardly and downwardly so as to collapse the parallelogrammatic base structure, the display members 10 and 11 being automatically closely folded in the movement of the top section 6 of the base between said base section and the panel 8, as clearly shown in Fig. 4 of the drawing.

15 Thus, a large number of such devices may be very compactly arranged so as to occupy a minimum of space in shipment or storage. It is also apparent that in view of the simple and durable construction of the several cooperating elements, the

20 device may be repeatedly folded or collapsed without impairing the proper operation thereof or distorting or otherwise damaging the relatively movable elements.

From the foregoing description considered in connection with the accompanying drawing, the construction, manner of use and several advantages of my display device will be clearly and fully understood. It will be seen that I have provided an article of this character which lends itself to use in the attractive design display of various commodities or the purposes to which merchandise of different kinds may be applied. Therefore, while I have illustrated one example of a display embodying my present improvements, it is of course evident that in accordance with the particular commodity to be advertised, such device may be produced in various other shapes or sizes, and the several structural parts thereof modified as the occasion might require. Accordingly, it is understood that I reserve the privilege of resorting to all such legitimate changes therein as may be fairly incorporated within the spirit and scope of the invention as claimed.

I claim:

- 50 1. A display device of the character described comprising a collapsible, parallelogrammatic base structure having a top section provided with a slot therein, a display member hingedly connected with said base structure and movable through said slot, a panel fixed at one of its ends to one edge of the base structure and movable therewith to and from superimposed relation upon the base structure, and means on said base structure adjustable into cooperative relation with said panel and a part of the base structure to rigidly sustain said panel and base structure against collapse.
- 55 2. A display device of the character described comprising a collapsible, parallelogrammatic base structure having a top section provided with a slot therein, a display member hingedly connected with said base structure and movable through said slot, a panel fixed at one of its ends to one

edge of the base structure and movable therewith to and from superimposed relation upon the base structure, and means on said base structure adjustable into cooperative relation with said panel, a part of the base structure and said movable display member to rigidly sustain said member, the base structure and said panel against relative movement.

3. A display device of the character described comprising a collapsible, parallelogrammatic base structure having a top section provided with a slot therein, a display member hingedly connected with said base structure and movable through said slot, a panel fixed at one of its ends to one edge of the base structure and movable therewith to and from superimposed relation upon the base structure, said base structure also including a bottom section and a part hingedly connected with the bottom section to project rearwardly from said panel, and having means cooperating with parts of said panel, the top section of the base and said display member to rigidly sustain the same in their relative set-up positions and prevent the collapse of the device.

4. A display device of the character described comprising a display panel, a base structure including upper and lower members, said members at corresponding edges thereof being hingedly connected to the lower end of the panel in vertically spaced relation to each other, means connecting the said members with each other in spaced relation from the panel for relative movement when said panel is folded downwardly into superimposed position upon the upper base member, a display part hingedly connected at one of its ends to the lower base member in spaced relation from the panel, and said upper base member having a slot through which said display part is slidably movable to and from an erect position relative to the base structure in the movement of said base members relative to each other.

5. A display device of the character described comprising a display panel, a base structure including upper and lower members, said members at corresponding edges thereof being hingedly connected to the lower end of the panel in vertically spaced relation to each other, means connecting the said members with each other in spaced relation from the panel for relative movement when said panel is folded downwardly into superimposed position upon the upper base member, a display part hingedly connected at one of its ends to the lower base member in spaced relation from the panel, and said upper base member having a slot through which said display part is slidably movable to and from an erect position relative to the base structure in the movement of said base members relative to each other, said lower member of the base structure, including a hingedly movable part thereof, adjustable to and from a position in the plane of said member, and having means cooperating with said panel and a part on the upper member of said base structure to rigidly sustain said panel and the upper and lower members of the base structure against relative collapsing movement.

IRA G. HAAS.
